UNITED STATES PATENT OFFICE.

OSCAR L. LAWSON, OF LYNN, MASSACHUSETTS, ASSIGNOR OF ONE-HALF TO CARL ANDERSON, OF LOWELL, MASSACHUSETTS.

THREAD PULL-OFF AND LOCKING DEVICE.

1,217,871.

Specification of Letters Patent. Patented Feb. 27, 1917.

Application filed August 27, 1914. Serial No. 858,825.

To all whom it may concern:

Be it known that I, OSCAR L. LAWSON, subject of the King of Sweden, residing at Lynn, county of Essex, State of Massachusetts, have invented a certain new and useful Improvement in Thread Pull-Off and Locking Devices, of which the following is a specification, reference being had therein to the accompanying drawings.

10. My invention has to do with sewing machines for use in the manufacture of leather goods such as boots and shoes, harness and the like, and particularly with sole stitching machines employing a waxed thread. The 15 particular object of the invention is to provide a thread pull off and locking device which will be dependent on the thickness of the stock being sewn for correct operation so that the lock of the stitch will always be located at a pre-determined distance from the surface of the stock. To this end, I have provided a thread pull-off and locking device which is operated by a movable presser foot resting upon the work, 20 the parts being automatically actuated in time with the remainder of the machine. The result is that when a thin piece of stock is beneath the presser foot, a short length of thread is furnished to the stitch 25 forming instrumentalities, while when a thick portion of stock is beneath the presser foot a proportionally longer length of thread is pulled off, and the stitches, regardless of their length are drawn down 30 with uniform tension by the thread clamp so that the lock of the stitch is always placed at a uniform depth. The device shown and described herein is an improvement on that disclosed in my prior application for sole 35 stitching machine filed May 29, 1914, Ser. No. 841,752.

For convenience of illustration, I have shown my invention as applied to the sole stitching machine shown in my said prior application but it will be apparent to those skilled in the art that it may be easily applied to other machines for the same purpose.

The invention will be fully understood 50 from the following description taken in connection with the accompanying drawings and the novel features thereof will be pointed out and clearly defined in the claims at the close of the specification.

55. In the drawings, Figure 1 is a side ele-

vation of the parts of a sole stitching machine embodying my present invention.

Fig. 2 shows the thread pull off and locking mechanism in the position which they occupy when the amount of thread necessary for one stitch has been pulled off.

Fig. 3 is a front elevation of the parts shown in Fig. 2.

Referring now to the drawings, there is shown at 4 the work support of a sole stitching machine of the type described in my application hereinbefore referred to. At 5 is shown the presser foot which is actuated by the slotted arm 6 mounted on the disk 7 which is periodically rocked. At 18 is shown a link or pendant arm having its lower end formed into a wedge 100 for a purpose to be hereinafter explained. The upper end of said link 18 is pivoted at 30 to the rear end of the arm 9 on which the presser foot 5 is mounted, said arm 9 is fulcrumed intermediate its ends by pivot connection with the frame. Therefore, when the presser foot 5 is raised, the wedge 100 is lowered a distance proportional to the amount of movement of the presser foot. Thus the wedge 100 will be lowered a greater distance when a thick portion of the stock is passing beneath the presser foot than when a thin part is under the presser 85 foot.

At 11 is shown the main shaft of the machine. On it is located a wiper cam 12 which contacts with the back of the link 18 on which is formed the wedge 100. At 14 is shown a pivot on which are mounted the two members 13 and 19, having two half-round arms 15 and 20, the flat surfaces of which normally lie in contact with each other. The member 13 is in the form of a bell-crank having an arm 31 on the lower end of which is a stud 17 which contacts with the wedge 100 on the lower end of the link 18. It will be seen therefore that at each revolution of the shaft 11 the cam 100 pushes the link 18 to the right as seen in Fig. 1, and the wedge surface 100 on the link in turn contacts with the stud 17 and swings the bell-crank 13 about its pivot 14 raising the half round arm 15. It will also be seen that the amount of movement imparted to the half round arm 15 will depend upon the position of the wedge 100, the travel of the arm 15 being increased as the wedge 100 is lowered.

At 22 is shown a rest through a hole 32 in which the thread 34 passes to the wax pot. The thread 34 passes from the ball or other thread supply between the upper 5 surface of the rest 22 and the under surface of the half round arm 20, then over the half round arm 15 on the thread pull off lever and then down through the hole 32 in the rest 22 to the wax pot, whence it passes up to 10 the stitch forming instrumentalities, said latter parts not being shown in the drawings. A spring 21 holds the arm 20 down against the rest 22 and pinches the thread between arm 20 and the rest except at certain 15 times so that the thread is held firmly during the formation of the stitch. It will also be seen that as the thread passes around the two half round arms and between them and the rest 22, the strain on the thread 20 during the formation of the stitch tends to pinch the thread the more firmly between the half round arm and the rest.

The pressure exerted on the arm 19 by the spring 21 in part determines the tension 25 on the thread and at all times during the operation of the machine exerts a certain pressure on the thread.

At 23 is shown a stud on the link 18 so placed that it will contact with the tail 33 30 of the lever 19 and lift the arm 20 out of contact with the rest 22 and permit the thread to be pulled out freely whenever the presser foot is raised above a pre-determined point as for instance when the work 35 is being taken out of the machine.

The operation of my improved thread pull off and locking device is as follows:— When it is desired to insert the work the 40 presser foot is raised thus releasing the pressure normally exerted on the thread by the thread clamp 20. The thread may then be pulled out for a sufficient distance to insure the operation of the stitch forming instrumentalities. The presser foot is then 45 lowered into normal position allowing the spring 21 to exert the normal tension on the thread through the thread clamp 20. Thereafter, each time the main shaft 11 revolves and a stitch is formed by the stitch 50 forming parts (not shown), the thread pull off arm will be raised, thereby drawing from the thread supply the amount of thread which is necessary for the formation of a stitch in the thickness of stock then being

presented to the needle. The length of 55 thread thus pulled off depends on the position of the presser foot which moves the wedge 100 vertically as previously described. When the cam 12 has moved out of contact with the link 18, the pull off arm 60 15 is released and drops down into contact with the thread clamp 20, so that thereafter the thread is pinched against the rest 32 and held firmly.

What I claim is:

1. In a sewing machine the combination 65 with stitch forming instrumentalities of two members normally in contact with each other, the thread passing entirely around the said combined two members, a rest below 70 said members between which and one of said members the thread passes, and means to move the other of said two members periodically in time with the stitch forming instrumentalities.

2. In a sewing machine having periodically moving stitch forming instrumentalities and a presser foot, the combination of a rest, two pivoted members adjacent each other one of which clamps the thread to the 80 rest, means for normally holding said clamp member in operative position, the other of said pivoted members normally resting in contact with the said pivoted clamp member, the thread passing between the said rest 85 and the said pivoted clamp member and entirely around the combined two pivoted members, and means to move the other one of said two pivoted members away from and toward the said pivoted clamp member periodically and in time with the stitch forming 90 instrumentalities.

3. In a sewing machine, the combination 95 with stitch forming instrumentalities of two half-round members having their flat sides normally in contact with each other and about which the thread passes, a rest below 100 said members between which and the lower member the thread passes, and means to move one of said members periodically in time with the stitch forming instrumentalities.

In testimony whereof I affix my signature, in presence of two witnesses.

OSCAR L. LAWSON.
